(57) **CLAIM**

The ornamental design for an uninterruptible power supply,
as shown and described.

DESCRIPTION

FIG. 1 is a perspective view of an uninterruptible power
supply, showing our new design;

FIG. 2 is a front elevation view thereof;

FIG. 3 is a back elevation view thereof;

FIG. 4 is a right side elevation view thereof; the left side
elevation view is a mirror image thereto; and,

FIG. 5 is a top plan view thereof.

The broken line showing of the environment is for illustrative
purposes only and forms no part of the claimed design.
